BOTTLE AND CAN CONTAINER AND CARRIER

Nino J. Nemesio, Sioux City, Iowa

Application December 29, 1952, Serial No. 328,275

1 Claim. (Cl. 220—103)

This invention relates to packaging devices and particularly carriers for soft drink bottles in which the bottles are exposed, and in particular a carrier in which the bottles or other containers are horizontally positioned and from which the bottles may be withdrawn as desired.

The purpose of this invention is to provide a carrier for soft drink bottles, cans, and other containers in which the device is in the form of a suitcase and in which bottles are frictionally held with inclined flaps so that they may readily be removed.

Carriers for soft drink bottles, beer cans and the like have been provided in various forms, however, with the conventional type of bottle carrier it is difficult to stack the carriers and, consequently, unnecessary storage space is required in warehouses, trucks, and retail stores. With this thought in mind this invention contemplates a carrier which is in the form of a rectangular shaped block in which bottles are stored in horizontally disposed positions and in which a handle is provided by cutting slots in the upper surface.

The object of this invention is, therefore, to provide an improved carrier for soft drink bottles, cans and other containers in which the carrier is of a rectangular shape.

Another object of the invention is to provide an improved carrier for bottles, cans and other containers in which the containers are frictionally held and from which the containers may readily be removed.

A further object of the invention is to provide an improved carrier for soft drink bottles, cans and other containers in which the carrier is of a simple and economical construction.

With these and other objects and advantages in view the invention embodies a rectangular shaped or box-like carton having an open side with diagonally positioned flaps at the upper and lower edges, with doors having elongated bottle neck receiving slots hinged to the ends and positioned to fold against a center supporting web and with slots in the upper surface to provide a handle.

Other features and advantages of the invention will appear from the following description taken in connection with the drawings, wherein:

Figure 1 is a side elevational view of the improved carrier showing a plurality of soft drink bottles positioned in the carrier.

Figure 2 is an end elevational view of the carrier showing the necks of the bottles extended from one side thereof.

Figure 3 is a cross section through the carrier taken on line 3—3 of Fig. 1 showing outwardly extended panels for a name or advertising matter on the side opposite to that from which the necks of the bottles extend.

Figure 4 is a perspective view showing the diagonally disposed flaps on the edges of the sides of the carrier, the center supporting web, and the hinged doors with the elongated slots therein.

Figure 5 is an elevational view looking toward the base or side of the carrier opposite to the side shown in Fig. 1.

Figure 6 is a cross section through the carrier taken on line 6—6 of Fig. 4.

Figure 7 is a longitudinal section through the carrier taken on line 7—7 of Fig. 4 and with the doors broken away.

Figure 8 is a detail showing a section taken on line

2

8—8 of Fig. 4 illustrating the mounting of one end of the center supporting web.

Figure 9 is a detail illustrating a reinforcing member extended across the slot in one end of the carrier whereby 5 a handle is provided in said slot.

Figure 10 is a longitudinal section similar to that shown in Fig. 7 wherein the center supporting web is of double thickness.

Figure 11 is a detail illustrating the construction of 10 the said center supporting web wherein the web is formed of a single strip of material bent midway of the length thereof and having flanges on the extended ends.

Figure 12 is a detail illustrating a further modification 15 wherein the carrier is provided with a handle secured to the outer surface.

Figure 13 is a front elevational view similar to that shown in Fig. 1 with the bottles and doors omitted and with parts broken away showing connections of the center supporting web to the sides of the carrier.

Figure 14 is a cross section through the carrier shown 20 in Fig. 13 being taken on line 14—14 thereof.

Figure 15 is a plan view of the carrier as shown in Fig. 13 also with the doors omitted.

Figure 16 is a longitudinal section through the carrier 25 taken on line 16—16 of Fig. 15 showing a modification wherein individual trays are positioned in the carrier, and wherein the trays are secured together with staples.

Figure 17 is a front elevational view of the carton 30 also similar to that shown in Fig. 1 with the bottles omitted and illustrating a further modification wherein the carrier is provided with a longitudinally disposed partition or supporting web.

Figure 18 is also a front elevational view of a carrier 35 or carton similar to that shown in Fig. 1 with the bottles omitted and illustrating a still further modification wherein the carrier is provided with both longitudinally disposed and transversely disposed supporting webs.

Referring now to the drawings wherein like reference 40 characters denote corresponding parts the improved container carrier of this invention includes a base 10, end walls 11 and 12, an upper panel 13, a rear wall 14, a center supporting web 15 and doors 16 and 17.

The base 10 is substantially rectangular-shaped and the 45 forward edge is provided with a diagonally disposed flap 18. The upper panel 13 is of a shape similar to that of the base and the extended edge is also provided with a diagonally disposed flap as indicated by the numeral 19.

The end walls 11 and 12 are provided with lining strips 50 20 and 21 respectively and the strips are provided with inwardly extended sockets 22 and 23, respectively in which the ends of the doors 16 and 17 are secured by staples as indicated by the numeral 24.

The door 16 is provided with a flap 25 having a V-shaped notch 26 therein and elongated slots 27 and 28 55 are positioned in the intermediate part of the door forming a center bar 29. The bar 29 is provided with an opening 30 to facilitate withdrawing the door from the closed position as shown in Fig. 1.

The door 17 is provided with a flap 31 having a V-shaped notch 32 therein and this door is provided with elongated slots 33 and 34 providing a center bar 35. The bar 35 is provided with an opening 36, similar to the opening 30 in the bar 29.

The upper panel 13 is formed with parallel elongated 60 slots 37 and 38 and reinforcing strips 39 and 40, positioned behind or against the inner surface of a bar 41 between the slots 37 and 38 are secured to the upper panel with staples 42. By this means a handle is provided for carrying the device.

The carrier is provided with reinforcing means including the center support 15, one end of which is secured to the base 10 with staples 43 extended through a flange 44 and the opposite end is secured to the upper panel 13.

The end walls, ends of the doors and inner lining panels 70 75 are provided with openings, as indicated by the numeral 45, to facilitate picking up the carrier by the end walls and, as illustrated in Fig. 4, the base 10 and upper panel 13 are secured to the end walls with staples 46 that extend through flanges 47. It will be understood that the parts may be secured together by other suitable means.

The intermediate portion of the rear wall 14 is pressed

inwardly providing an embossed or extended panel 48 on which the name of the product, for which the carrier is intended, or other advertising matter may be placed.

With the parts formed in this manner bottles, as indicated by the numeral 49 are positioned in layers in the carrier with the necks of the bottles extended from the open side and with the lower and upper rows of bottles held by the flaps 18 and 19 and the intermediate rows held by the doors through the slots of which the necks of the bottles extend.

The inner edges of the inner lining strips or panels 20 and 21 that are positioned against the inner surfaces of the end walls 11 and 12, respectively are provided with flanges 50 which may be secured, by an adhesive, or other suitable means to the rear wall 14. The connections between the parts of the improved container carrier may be formed with flanges and staples or with an adhesive or other means.

In the design illustrated in Fig. 10 a container having a base 51, end walls 52 and 53, a rear wall 54 with an extended panel 55 therein and a cover panel similar to the upper panel 13 of the container shown in Fig. 4, is provided with a center support or partition formed with a strip of material bent about midway of its length to form side sections 56 and 57, the ends of which are secured to the base 51 and upper panel, respectively.

The center support may also be formed as illustrated in the modification shown in Fig. 11 wherein a strip of material is bent midway of its length to form side sections 58 and 59 and the sections 58 and 59 are provided with flanges 60 and 61.

In Fig. 12 the handle 62 that is adapted to be secured to the outer surface of the carrier is illustrated and, as shown, the handle is provided with end sections 63 and 64 from which flanges 65 and 66 extend. The flanges are provided with folded over ends 67 and 68. With handles of this type the flanges 65 and 66 are adapted to be secured to the surface of a container by adhesive or other means and the handle may be located at a suitable point or at points on the carrier. In this design the handle is positioned on the upper panel, as indicated by the dot and dash lines 69 and the handle is positioned to straddle the center support or partition 70.

In the design illustrated in Fig. 13 a carrier 71 similar to the carrier illustrated in Fig. 1 is provided with a continuous inner tray 72 and the tray is formed with a continuous liner 73. In this design the center support 74 is similar to the support shown in Fig. 11, having flanges 75 and 76 with which the support is secured at the lower side or base to a strip of material 77 similar to the reinforcing strip 73 and by this means an upper panel 78 is supported from a base 79.

In the design shown in Fig. 14 the walls of the tray 72 are provided with diagonally disposed or beveled flanges 73, similar to the flaps 18 and 19 of the carton shown in Fig. 4 and these flanges or flaps are nested under flaps 74 and 75 corresponding to flaps 18 and 19. Also in this design an end wall 76 is provided with a hand gripping opening 77 and a rear wall 78 is provided with an offset section 79.

In the design illustrated in Figs. 15 and 16 individual trays 80 and 81 are positioned in a carrier 82 similar to the carrier shown in Fig. 1 and the trays 80 and 81 are secured together, at the center, with staples 83. The body of the carrier is, otherwise, similar to that of the carrier shown in Fig. 4.

In the design illustrated in Fig. 17 a carrier 84 is provided with a horizontally disposed longitudinally extended partition 85 in which a continuous strip of material is bent midway of its length and the ends of the 70

sections thereof are provided with flanges 86 and 87 that are secured to end walls of an inner tray or container 88. The tray 88 is nested in the carrier 84 and the edges are provided with corresponding diagonally disposed flaps, as indicated by the numerals 89 and 90.

In Fig. 18 a carrier 91, also similar to the carrier illustrated in Fig. 4 is provided with a longitudinally disposed support member 92 and the member 92 is secured to an end wall 93 of the carrier with flanges 94 and 95. 10 In this design a center supporting panel 96 extends through the member 92, dividing the carrier into four individual compartments.

It will be understood, therefore, that the carrier may be provided in different designs and the bottles, cans, or other product holding containers may be secured in the carrier by other suitable means.

It will be understood that modifications, within the scope of the appended claim, may be made in the design and arrangement of parts without departing from the spirit of the invention.

What is claimed is:

A carrier for containers having a reduced neck portion comprising a base, a pair of spaced parallel end walls extending upwardly from said base, an upper panel extending between the upper ends of said end walls, a web extending transversely between said base and panel, said base having a rectangular shape and including an angularly arranged flap, said panel being provided with an angularly arranged flap, lining strips arranged contiguous to the inner surfaces of said end walls and secured thereto, each of said strips including a central inwardly offset portion defining a socket, a first door having a portion secured in one of said sockets, a second door having a portion secured in the other of said sockets, there being a pair of spaced slots in the intermediate portion of each of said doors defining a center bar in each door, the longitudinal axis of said slots being parallel to the longitudinal axis of said base when the doors are in closed condition, each of said bars being provided with a finger engaging opening, said upper panel including a pair of spaced parallel slots defining a bar, reinforcing strips mounted adjacent to the inner surface of said last named bar, said web having end portions secured to the inner surfaces of said panel and base, there being openings in the end walls of said carrier, the angularly arranged flaps on said base and panel engaging portions of the outermost containers positioned in the carrier, the neck portions of other containers projecting through the slots in said doors.
